WINDOW WASHING AND WIPING DEVICE

Edward W. Collins, Chicago, Ill.

Application July 18, 1950, Serial No. 174,470

5 Claims. (Cl. 15—244)

1

My invention relates to hand-operated devices employed for washing windows, and more particularly to that class of devices which are applicable to the outer side of the inner sash when the same is raised in order to wash such outer side.

It is a comparatively easy matter, when the inner sash of a window has been raised, to reach the outer side of the outer sash with a suitable implement to wash or clean the same, as the approach to such outer side is clear. However, when the outer side of the inner sash has to be treated after such sash has been partly raised, a device thin enough to be passed between the sashes must be had, and such devices of this character as have come to my attention have either been too involved, unhandy or unreliable.

My improvement deals especially with a feature to introduce a washing or wiping element in a position for easy passage between the sashes, and operate the device in a manner to tilt such element in the direction of the window pane for facility of application, and one object is to provide a device of this kind which is of a highly compact nature for the passage referred to, yet mechanically constituted to obtain the tilting action by positive means.

A further object is to provide a device of the above character which is formed with a flattened shank and compact headpiece for facilitating its passage between the window sashes, and to fit the headpiece with a novel gearing to procure the tilting action.

Another object is to provide a control at the lower end of the device which need be rotated only a quarter turn to procure the tilting action of the washing or wiping element.

An additional object is to construct the device with a minimum amount of weight consistent with sufficient strength and stiffness to maintain its shape, and with close assembling tolerances in order to seal its internal operating parts against dust or foreign matter.

An important object is to use a minimum number of parts consistent with a high degree of structural and functional efficiency in the novel device.

With the above objects in view, and any others which may suggest themselves from the description to follow, a better understanding of the invention may be had by reference to the accompanying drawing, in which—

Fig. 1 is an elevation of a typical house window as seen from the inner side, showing the application of the novel washing device;

2

Fig. 2 is an enlarged section of the upper portion of the device, partly broken away and showing a sponge-type applicator;

Fig. 3 is a section on the line 3—3 of Fig. 2;

Fig. 4 is a section of a squeegee-type applicator adapted to replace the sponge-type applicator of Fig. 3;

Fig. 5 is an elevation of the lower part of the device, partly in section;

Fig. 6 is a section on the line 6—6 of Fig. 5;

Fig. 7 is a section on the line 7—7 of Fig. 2; and

Fig. 8 is an elevation of a handle portion appearing in the center of Fig. 5.

15 In accordance with the foregoing, specific reference to the drawing indicates the frame 19 of a typical house window, 11 the inner sash and 12 the outer sash thereof. As seen in Fig. 1, the novel device is introduced—after the inner sash has been raised—to pass with its upper portion through the space between the sashes for application to the outer side of the inner sash. To facilitate the passage of the device as stated, its upper portion is made into a headpiece 15 of T-form; and the neck 16 of the headpiece is attached by means of pins 17 to the upper end portion of the shank 18 of the device. Such shank is preferably of double-ply sheet metal in thin or flat form and having a suitable amount of strength or stiffness, so that the shank will not bend or flex during ordinary use or handling.

20 The headpiece 15 is fitted at the top with an elongated frame 20, the latter being secured to the headpiece by screws 22. The ends 24 of the frame serve as bearings for the terminal trunnions 26 of a trough-like holder 30. The latter forms a seat for the similarly shaped base 32 of a sponge-like washing element 33 or squeegee 34. The base 32 has transversely projecting 25 studs 35 and 36 near the ends; and the holder 30 has undercut slots 38 into which the studs 35 may be backed when the corresponding end of the element 33 is inserted into the holder 30. At such time a pair of slots 40 made near the 30 opposite end of the holder will be in a position to receive the studs 36 while the cleaning element base 32 fits into the holder 30 with friction when the base of the element 33 is fitted into the holder. The element 33 is thus removably attached to the device for the washing function; and it can be removed by drawing on outward flanges 32a of the holder 30 and replaced by the squeegee element 34 when the wiping function is to be instituted.

55 The normal position of the elements 33 and

34 is extended, as in Figs. 2, 3 and 4; and the thickness of those elements is made less than the width of the space between the window sashes, so that the device may be passed with its upper portion through such space to a position such as shown in Fig. 1. When this position has been attained, the handle 45 at the lower end of the device is designed to be given a partial turn with the effect of rotating or tilting the element 33 or 34 to a position at right angles with the shank 18 of the device. Thus, when the tilt is toward the outer side of the inner sash, the element 33 or 34 is positioned for frictional engagement with the window pane to accomplish the washing or wiping of the same.

As noted in Fig. 5, the handle 45 receives the lower end of a shaft 50 which rises through a tubular stem 51 secured by rivets 52 to the lower end of the shank 18, the shaft rising freely through the stem 51 and between the walls of the shank; and a cross-pin 55 passing through the lower end portion of the shaft and the handle 45 serves to connect these parts for joint rotation.

Fig. 2 shows that the shaft 50 rises into the neck 16 of the headpiece 15 to terminate with a horizontal spur gear 58 located in a pocket 59 in the center of the headpiece. The pocket 59 has a top enlargement 60 in a longitudinal direction seating a bar 62 of square cross-section. Fig. 7 shows that this bar has an intermediate circular enlargement 63 which serves to journal a spur gear 64 made with a lateral gear segment 65 which is in mesh with the spur gear 58. The spur gear 64 rises through a slot 66 in the frame 20 to mesh with a part-circular spur gear 68 which is welded or otherwise rigidly secured in a cavity 69 made in the floor of the holder 30. Thus, turning the handle 45 in relation to the shank 18 transmits motion through the gear 58, segment 65, gear 64 and gear 68 to rotate the holder 30 on the trunnions 26 and procure the tilt of the washing or wiping element previously referred to. It is of course an easy matter to operate the handle 45 with one hand while the shank 18 is held with the other.

Fig. 8 shows that the upper end of the handle 45 has a cavity 70 whose ends form limits relative to a side pin 72 projecting from the tubular stem 51 when the handle is turned. When the turn is in a direction to tilt the washing or wiping element as previously described, it is desirable to lock the element against return action as the device is pulled downwardly with pressure on the washing or wiping element. Fig. 8 shows a spring 73 secured with one end to the handle 45 and formed with a hook 74 at the other end seating and locked by the pin 72 in the advanced position. The hook 74 has a stem 75 which may be raised to clear the pin when the handle is turned in the returning direction, as per arrow. When the handle is again operated to procure the tilt of the washing or wiping element, the spring will trip the pin and reset itself to lock the handle from the returning movement.

It will now be apparent that the novel device has a number of advantageous features. First, it is narrow enough when its washing or wiping element is in the normal or extended position to fit between the sashes of any conventional or house window in order to locate the washing or wiping element in the zone of application. Further, the gearing is designed to obtain the tilt of the washing or wiping element to a right angle merely by imparting a quarter-turn to the

handle. Further, the headpiece is made with a holder in which the sponge washing element is quickly interchangeable with the squeegee wiping element and vice versa. Further, the device is of a nature to be made of stainless steel or aluminum in order to prevent rust or corrosion. Finally, the device has its mechanism fully enclosed and designed with fine limits or tolerances in order to protect the mechanism from dust, foreign matter or damage; and to combine its efficient operation with compactness, making the device neat in appearance and easy to handle.

While I have described the invention along specific lines, various minor changes or refinements may be made therein without departing from its principle, and I reserve the right to employ all such changes and refinements as may come within the scope and spirit of the appended claims.

I. claim:

1. A window cleaning implement comprising a substantially T-shaped member receiving a handle at its lower end, a holder journaled in the head of the member to be rockable in a plane transverse of said head, a window cleaning element carried by the holder and normally projected therefrom in a direction opposite from the shank of the member, and means operated by the rotation of the handle to rock the holder and tilt said element to a position at an angle to the shank for edgewise application to the window, the shank having a longitudinal bore, and said means comprising a shaft connected to the handle at one end and passing through said bore to terminate with its other end in a cavity made in the headpiece, a spur gear carried by said other end, a second spur gear journaled in the head at right angles to the first spur gear, a third spur gear carried by said holder and in mesh with the second spur gear, and a gear projecting from the face of the second spur gear in meshing relation with the first spur gear.

2. A window cleaning implement comprising a substantially T-shaped member receiving a handle at its lower end, a holder journaled in the head of the member to be rockable in a plane transverse of said head, a window cleaning element carried by the holder and normally projected therefrom in a direction opposite from the shank of the member, and means operated by the rotation of the handle to rock the holder and tilt said element to a position at an angle to the shank for edgewise application to the window, the shank having a longitudinal bore, and said means comprising a shaft connected to the handle at one end and passing through said bore to terminate with its other end in a cavity made in the head, a spur gear carried by said other end, a second spur gear journaled in the head at right angles to the first spur gear, a third spur gear carried by said holder and in mesh with the second spur gear, and a gear projecting from the face of the second spur gear in meshing relation with the first spur gear, the journal of the second spur gear comprising a bar lodged in the head in a longitudinal direction and crossing said cavity, such bar being in non-rotatable relation with the head and having a circular portion in the region of the second spur gear, and the latter being bored for rotation on said circular portion.

3. A window cleaning implement comprising a substantially T-shaped member receiving a handle at its lower end, a holder journaled in

the head of the member to be rockable in a plane transverse of said head, a window cleaning element carried by the holder and normally projected therefrom in a direction opposite from the shank of the member, and means operated by the rotation of the handle to rock the holder and tilt said element to a position at an angle to the shank for edgewise application to the window, the shank having a longitudinal bore, and said means comprising a shaft connected to the handle at one end and passing through said bore to terminate with its other end in a cavity made in the head, a spur gear carried by said other end, a second spur gear journaled in the head at right angles to the first spur gear, a third spur gear carried by said holder, and in mesh with the second spur gear, and a gear projecting from the face of the second spur gear in meshing relation with the first spur gear, the journal of the second spur gear comprising a bar lodged in the head in a longitudinal direction and crossing said cavity, such bar being of square cross-section to be non-rotatable relative to the head and having a circular portion in the region of the second spur gear, and the latter being bored for rotation on said circular portion.

4. A window cleaning implement comprising a substantially T-shaped member receiving a handle at its lower end, a holder journaled in the head of the member to be rockable in a plane transverse of said head, a window cleaning element carried by the holder and normally projected therefrom in a direction opposite from the shank of the member, and means operated by the rotation of the handle to rock the holder and tilt said element to a position at an angle to the shank for edgewise application to the window, the holder being of longitudinal trough form, and said element having a base of similar form designed to removably fit into the holder, the latter having undercut slots in its edges near one end, pins carried by the base and designed to enter said slots on the fitting of the related end of the base into the holder, transverse slots in the edges of the holder near the

other end, and other pins carried by the base in the regions of the transverse slots and designed to fit into the same on the application of the corresponding end of the base to the holder.

5. A window cleaning implement comprising a substantially T-shaped member receiving a handle at its lower end, a holder journaled in the head of the member to be rockable in a plane transverse of said head, a window cleaning element carried by the holder and normally projected therefrom in a direction opposite from the shank of the member, and means operated by the rotation of the handle to rock the holder and tilt said element to a position at an angle to the shank for edgewise application to the window, the holder being of longitudinal trough form, and said element having a base of similar form designed to removably fit into the holder, the latter having undercut slots in its edges near one end, pins carried by the base and designed to enter said slots on the fitting of the related end of the base into the holder, transverse slots in the edges of the holder near the other end, and other pins carried by the base in the regions of the transverse slots and designed to fit into the same on the application of the corresponding end of the base to the holder, the latter being tensionable by the fitting of the base to grip the same as the base is fitted therein.
